UNITED STATES PATENT OFFICE.

ELIAS E. SLAGHT, OF TORONTO, ONTARIO, CANADA.

TOBACCO-PIPE.

1,107,716.

Specification of Letters Patent. Patented Aug. 18, 1914.

Application filed January 21, 1913. Serial No. 743,374.

To all whom it may concern:

Be it known that I, ELIAS E. SLAGHT, of the city of Toronto, in the Province of Ontario, Canada, have invented certain new 5 and useful Improvements in Tobacco-Pipes, of which the following is a specification.

My object in the construction of this pipe is to insure to the smoker a cool dry smoke without increasing the cost of the pipe and 10 without spoiling its appearance.

I attain my object by forming in the stem of the pipe two chambers separated by an apertured diaphragm. The chambers communicate respectively with the bore of the 15 pipe and its mouthpiece at points distant from the walls of the chambers, so that each chamber may contain a considerable quantity of liquid which cannot flow back either through the mouthpiece or through the 20 bowl. The outer walls of the chamber are preferably formed by a metal ferrule which is a good conductor of heat and thus serves to cool the smoke.

The pipe is constructed in detail substantially as hereinafter more fully described and illustrated in the accompanying drawings in which—

Figure 1 is a longitudinal section of my improved pipe. Fig. 2 is an enlarged section of the diaphragm. Fig. 3 is a front elevation of the same. Fig. 4 is an enlarged section of a modified form of diaphragm. Fig. 5 is front elevation of the same and Fig. 6 a longitudinal section of the ferrule.

35 In the drawings like numerals of reference indicate corresponding parts in the different figures of the drawings.

My invention is equally applicable to pipes or cigar and cigarette holders and it 40 will be understood therefore that the expression "pipe" is to be taken to mean any device for the smoking of tobacco in any form.

In the drawings 1 is the stem of the pipe. 45 The end of this stem is reduced in diameter as shown to form the short tube 2. The adjacent end of the mouthpiece 3 is similarly turned down to form the short tube 4. A ferrule 5 is frictionally fitted on the adjacent 50 ends of the stem and mouthpiece and is so proportioned that the ends of the tubes 2 and 4 are separated sufficiently to leave room for a central diaphragm dividing the space within the ferrule into two chambers 55 6 and 7. The diaphragm is preferably formed of two disks 8 having flanged edges

which give them a bearing against the inner surface of the ferrule. Co-incident holes are formed in the disks forming an aperture 9, preferably located near the upper side of 60 the diaphragm. The aperture being out of line with the bore of the pipe it is impossible for any particles to be drawn straight across the chamber from the pipe stem to the mouthpiece. The chamber 7 collects any 65 saliva which may pass down from the mouth and the chamber 6 any juices or moisture from the tobacco. There is thus no opportunity afforded for moisture from the mouth passing down the pipe and wetting the tobacco which I find to be one of the most important causes of the fouling of the pipe. The smoke is also cooled and any particles therein entrapped by the said chambers owing to the circuitous path the smoke is 70 75 compelled to follow. This effect is enhanced by stamping in each disk 8 a projecting deflector 10 preferably contacting with the tubes 2 and 4 just above the openings therein. The smoke is thus prevented passing in straight lines from the openings in the tube 2 to the opening 9 or from the latter to the opening in the tube 4 but is compelled to circulate in the chambers 6 and 7. The effect may be still further enhanced by spacing the disks 8 to form between them a 80 85 chamber 11 as shown in Figs. 4 and 5.

It has been clearly shown that the pipe will safely entrap any foul juices and solid particles which might be sucked up into the 90 mouth and it will also be seen that the pipe is scarcely, if any, more expensive to make than an ordinary pipe.

The tubes 2 and 4 being integral with the stem and mouthpiece are formed on the latter when they are made at no increase of cost. A ferrule is commonly employed on pipes so that the disks forming the diaphragm are the only parts involving extra expense and these are very cheaply stamped 100 and placed in position. The chamber 11 may be fitted with gauze to act as a smoke strainer and this gauze may be medicated or perfumed if desired.

It will be seen that the ferrule 5 is easily 105 removed and boiled or otherwise cleaned.

What I claim as my invention is:—

1. In a pipe the combination of the stem having an end of reduced diameter integral therewith forming a short projecting tube; 110 a mouth-piece having a similar integral end of reduced diameter forming a short tube;

a ferrule connecting the stem and mouth-piece so proportioned that the ends of the said short tubes are separated; and an apertured diaphragm dividing the space within said ferrule into two chambers, said diaphragm adjacent the aperture therein being stamped to form a deflector projecting into one of the chambers across the direct path of smoke traveling across said chamber to 10 or from an axial passage of the pipe.

2. In a pipe the combination of the stem having an end of reduced diameter integral therewith forming a short projecting tube; a mouth-piece having a similar integral end of reduced diameter forming a short tube; a ferrule connecting the stem and mouth-piece so proportioned that the ends of the 15

said short tubes are separated; and an apertured diaphragm dividing the space within said ferrule into two chambers, said diaphragm being formed of two disks pressed into place and having an integral deflector formed thereon between the bore of the stem and the aperture in the diaphragm adapted to prevent smoke passing directly from one 20 to the other, substantially as shown and described.

Dated at Toronto this 16th day of Jan. 1913.

ELIAS E. SLAGHT.
